UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed October 18, 1924. Serial No. 744,320.

This invention relates to improvements in fan-fold or continuous billing typewriting machines, such as disclosed in the patent to Wernery and Smith, Serial No. 1,132,055, granted March 16, 1915, and relates to machines of this type in which there are two carbon-carriers, either of which may be used independently of the other, for operating on different work-webs.

10 Provision is herein disclosed whereby the typist is enabled to work with several different types of webs, and is enabled to quickly remove one of the webs from the machine for the substitution of another.

15 The present invention provides simplified means for spacing the rear carbon-holder slightly above its carrier truck so as to provide a passageway therebetween, for the webs associated with the front carbon-carrier to pass and thus permit the removal of said rear carbon-holder to replace it by another carbon-holder having a third work-web, without disturbing the work-web of the front carbon-carrier. The arrangement 20 also facilitates the rapid substitution of another web for the one associated with the front carbon-carrier. Heretofore it has been the practice to conduct the webs of the front carrier over the carbon-holder of the rear carrier, i. e., between the base of the carbon-holder and the carbon-supporting brackets or clips, with the result that the webs of both of said carriers were practically interlocked or inseparable from one 25 another.

30 A further feature of the invention is the provision of means for deflecting the leading portions of the work-webs of the front carbon-carrier downwardly behind the rear of the typewriter, so as to rest upon a supporting table which lies beneath the trackways of the carbon-paper-carriers.

35 Another feature is the provision of means for holding the rear carbon-carrier adjacent the rear of the machine while the forward carbon-carrier is being used.

40 Other features and advantages will hereinafter appear.

45 In the accompanying drawings, Figure 1 is a transverse section through a fan-fold machine, and showing my improvement applied thereto.

50 Figure 2 is a detail view of means for holding the bracket-plate of the rear carbon-carrier to the carrier-truck.

55 Figure 3 is a detail cross-section of a table for supporting the leading portions of the work-webs when out of use.

60 Figure 4 is a plan view of a deflector plate for the webs.

65 Figure 5 is a view of another type of table and deflector plate for the leading portions of webs when out of use.

70 Figure 6 is a plan view of a fan-fold machine, and showing my improvement.

75 A platen 10 may be mounted, as usual, in a platen-displacing frame 11 to swing about a transverse shaft 12 secured at its ends in a carriage 13, and may be rotated by means of a platen-knob 14 of the usual line-space mechanism. Feed-rolls 15 and 16 may be used to co-operate with a rear paper-table 17 in feeding work-sheets underneath and around the platen 10. A front paper-table 18 usually supports a gage-bar 19 on which is mounted a gage 20 for determining the position of the leading edges of work-sheet units to be severed from the webs. The frame 11 may be retained in normal position by means of a hook 21 which engages a pin 22 on said frame.

80 Supported by means of brackets 23, fastened to the rear of the carriage 13, may be the usual work-supporting frame 24. A transverse rod 25 may support by means of brackets 26 a work-supporting rod 27, the latter being provided with the usual paper-guides 28. Side members 29 of the work-supporting frame 24 are provided with rails 30 which support a front carbon-carrier A 85 and a rear carbon-carrier B. The front carbon-carrier A is of the usual construction and comprises a truck 31 having rollers 32 which ride upon the rails 30. A lever 33 is pivoted at 34 to swing into engagement with a slot of a pin 35, which projects from a bracket-plate or carbon-holder 36 through a perforation in the truck 31, as well known in machines of this type. The rear carbon-carrier B is similar to the front carbon-carrier A with the exception that the bracket-plate 37 is positioned somewhat above the truck 38, and for this purpose spacers 39 are employed adjacent both sides of the rear carrier, and may each comprise a length of sheet material bent as at 40 and 41, to provide feet 42 and platforms 39'. Screws 43

90 may be used for fastening the spacers 39 to the truck 38. The bracket-plate 37 is of the usual construction and includes pins 44 95 and 45. The front carbon-carrier A is supported by a transverse rod 46 which is secured to the front of the truck 31. The rear carbon-carrier B is supported by a transverse rod 47 which is secured to the rear of the truck 38. The front carbon-carrier A is supported by a transverse rod 48 which is secured to the front of the truck 31. The rear carbon-carrier B is supported by a transverse rod 49 which is secured to the rear of the truck 38. The front carbon-carrier A is supported by a transverse rod 50 which is secured to the front of the truck 31. The rear carbon-carrier B is supported by a transverse rod 51 which is secured to the rear of the truck 38. The front carbon-carrier A is supported by a transverse rod 52 which is secured to the front of the truck 31. The rear carbon-carrier B is supported by a transverse rod 53 which is secured to the rear of the truck 38. The front carbon-carrier A is supported by a transverse rod 54 which is secured to the front of the truck 31. The rear carbon-carrier B is supported by a transverse rod 55 which is secured to the rear of the truck 38. The front carbon-carrier A is supported by a transverse rod 56 which is secured to the front of the truck 31. The rear carbon-carrier B is supported by a transverse rod 57 which is secured to the rear of the truck 38. The front carbon-carrier A is supported by a transverse rod 58 which is secured to the front of the truck 31. The rear carbon-carrier B is supported by a transverse rod 59 which is secured to the rear of the truck 38. The front carbon-carrier A is supported by a transverse rod 60 which is secured to the front of the truck 31. The rear carbon-carrier B is supported by a transverse rod 61 which is secured to the rear of the truck 38. The front carbon-carrier A is supported by a transverse rod 62 which is secured to the front of the truck 31. The rear carbon-carrier B is supported by a transverse rod 63 which is secured to the rear of the truck 38. The front carbon-carrier A is supported by a transverse rod 64 which is secured to the front of the truck 31. The rear carbon-carrier B is supported by a transverse rod 65 which is secured to the rear of the truck 38. The front carbon-carrier A is supported by a transverse rod 66 which is secured to the front of the truck 31. The rear carbon-carrier B is supported by a transverse rod 67 which is secured to the rear of the truck 38. The front carbon-carrier A is supported by a transverse rod 68 which is secured to the front of the truck 31. The rear carbon-carrier B is supported by a transverse rod 69 which is secured to the rear of the truck 38. The front carbon-carrier A is supported by a transverse rod 70 which is secured to the front of the truck 31. The rear carbon-carrier B is supported by a transverse rod 71 which is secured to the rear of the truck 38. The front carbon-carrier A is supported by a transverse rod 72 which is secured to the front of the truck 31. The rear carbon-carrier B is supported by a transverse rod 73 which is secured to the rear of the truck 38. The front carbon-carrier A is supported by a transverse rod 74 which is secured to the front of the truck 31. The rear carbon-carrier B is supported by a transverse rod 75 which is secured to the rear of the truck 38. The front carbon-carrier A is supported by a transverse rod 76 which is secured to the front of the truck 31. The rear carbon-carrier B is supported by a transverse rod 77 which is secured to the rear of the truck 38. The front carbon-carrier A is supported by a transverse rod 78 which is secured to the front of the truck 31. The rear carbon-carrier B is supported by a transverse rod 79 which is secured to the rear of the truck 38. The front carbon-carrier A is supported by a transverse rod 80 which is secured to the front of the truck 31. The rear carbon-carrier B is supported by a transverse rod 81 which is secured to the rear of the truck 38. The front carbon-carrier A is supported by a transverse rod 82 which is secured to the front of the truck 31. The rear carbon-carrier B is supported by a transverse rod 83 which is secured to the rear of the truck 38. The front carbon-carrier A is supported by a transverse rod 84 which is secured to the front of the truck 31. The rear carbon-carrier B is supported by a transverse rod 85 which is secured to the rear of the truck 38. The front carbon-carrier A is supported by a transverse rod 86 which is secured to the front of the truck 31. The rear carbon-carrier B is supported by a transverse rod 87 which is secured to the rear of the truck 38. The front carbon-carrier A is supported by a transverse rod 88 which is secured to the front of the truck 31. The rear carbon-carrier B is supported by a transverse rod 89 which is secured to the rear of the truck 38. The front carbon-carrier A is supported by a transverse rod 90 which is secured to the front of the truck 31. The rear carbon-carrier B is supported by a transverse rod 91 which is secured to the rear of the truck 38. The front carbon-carrier A is supported by a transverse rod 92 which is secured to the front of the truck 31. The rear carbon-carrier B is supported by a transverse rod 93 which is secured to the rear of the truck 38. The front carbon-carrier A is supported by a transverse rod 94 which is secured to the front of the truck 31. The rear carbon-carrier B is supported by a transverse rod 95 which is secured to the rear of the truck 38. The front carbon-carrier A is supported by a transverse rod 96 which is secured to the front of the truck 31. The rear carbon-carrier B is supported by a transverse rod 97 which is secured to the rear of the truck 38. The front carbon-carrier A is supported by a transverse rod 98 which is secured to the front of the truck 31. The rear carbon-carrier B is supported by a transverse rod 99 which is secured to the rear of the truck 38. The front carbon-carrier A is supported by a transverse rod 100 which is secured to the front of the truck 31. The rear carbon-carrier B is supported by a transverse rod 101 which is secured to the rear of the truck 38. The front carbon-carrier A is supported by a transverse rod 102 which is secured to the front of the truck 31. The rear carbon-carrier B is supported by a transverse rod 103 which is secured to the rear of the truck 38. The front carbon-carrier A is supported by a transverse rod 104 which is secured to the front of the truck 31. The rear carbon-carrier B is supported by a transverse rod 105 which is secured to the rear of the truck 38. The front carbon-carrier A is supported by a transverse rod 106 which is secured to the front of the truck 31. The rear carbon-carrier B is supported by a transverse rod 107 which is secured to the rear of the truck 38. The front carbon-carrier A is supported by a transverse rod 108 which is secured to the front of the truck 31. The rear carbon-carrier B is supported by a transverse rod 109 which is secured to the rear of the truck 38. The front carbon-carrier A is supported by a transverse rod 110 which is secured to the front of the truck 31. The rear carbon-carrier B is supported by a transverse rod 111 which is secured to the rear of the truck 38.

fixed upon the under side thereof. The pins 44 project through perforations 46 in the platforms 39' and are slotted at 45 beneath said platforms to each receive the 5 blade 47 of a lever 48 pivoted at 49 to the under side of each of the platforms, so as to secure the bracket-plate 37 upon the truck 38. In the front carbon-carrier A, several 10 of the upper carbon-blades are omitted to leave room for the passage of the work-webs W of the rear carbon-carrier B to be run into the machine without interference. The rear carbon-carrier B has only top blades, all of the lower blades being omitted. 15 With particular attention to Figure 1, it will be seen that owing to the spacers 39, the webs W' carried by the front carbon-carrier A may be threaded through a passageway thus formed between the top of 20 the truck 38 and the under side of the bracket-plate 37, sufficient clearance being provided for the free movement of the webs. When out of use, the rear carbon-carrier B may be secured adjacent the rear of the 25 machine by means of a weak clip 50 mounted upon one of the side members 29 by means of a set screw 51, the clip being arranged to engage around a pin 52 carried upon the upper face of the truck 38. The usual 30 handles A' and B' are secured to their respective bracket-plates 36 and 37, and are operable to reciprocate their associated carbon-carrier back and forth during operation of the machine. Referring to Figures 1 and 35 6, reference numeral 53 represents a frame which extends rearwardly of the typewriting machine and supports the carbon-carrying structure above described. Extending across the frame 53 there is a table 54, which 40 has its ends resting upon the upper side portions of the frame, and is secured thereto by an offset plate 55, which engages under a ledge of the frame and is secured to the under side of the table by any suitable 45 means, such as rivets 56. The other side of the table is secured to the frame in a similar manner by means of an offset plate 57, but, instead of using rivets, the plate 57 may have a plurality of slots 58 through which 50 screws 57' project and are drawn up by nuts 58', so as to provide means whereby the table may be readily attached or removed from the frame when desired. A deflector plate 59 is disposed adjacent the rear of the 55 typewriting machine and is effective to deflect the leading portions of the webs W', carried by the front carbon-carrier A, downwardly behind the machine and onto the table 54, the latter providing a convenient 60 place for the reception of said leading portions when not in use. The deflector plate 59 is conveniently attached to the brackets 23 by means of arms 60, which are bent at 65 61 to engage around the brackets 23 and are securely clamped thereon by means of screws

62 which pass through suitable perforations in said arms and are drawn up by nuts 63. It will be seen that the deflector plate is also effective to guide the webs away from the tabulator stops and other mechanism 70 adjacent the rear of the typewriting machine, so as to prevent them from becoming entangled with the webs.

According to another form of construction, as illustrated in Figure 5, the deflector plate and table are formed as a single sheet of material providing a table portion 64 and curved upwardly, as at 65, adjacent the rear of the typewriter, to form a deflector 66. Legs 68 may be fixed to the table portions 64 by means of screws 67 and project upwardly to the side members 29 where they may be reduced and screw-threaded thereinto, as indicated at 69. It will be seen by this arrangement that the free end of the webs W', when out of use, may be led down at the rear of the machine and will be deflected by the curved portion 65 onto the table portion 64, where they will be carried with frame 24 as the same travels during 80 the movements of the carriage.

When the webs W of the rear carbon-carrier are out of use, the webs are generally thrown over the rear of said carrier, so as not to interfere with the manipulation of 85 the front carbon-carrier.

Thus, by a compact and simple device, provision is made whereby the rear carbon-holder may be quickly dismounted from its truck and a new holder and set of webs substituted therefor without disturbing the front carbon-carrier, or, a new web-carrying holder may be readily substituted for the front holder by simply releasing the rear holder from its truck, so as to permit the webs and holder of the front carrier to be removed.

Variations may be resorted to within the scope of the invention, and portions of the improvements may be used without others.

Having thus described my invention, I claim:

1. In a continuous billing typewriting machine, in combination, a platen around which may be fed separate sets of work-webs, a platen-carriage including a rearward extension, a front carbon-carrier and a rear carbon-carrier slidable on said extension, each of said carriers including a removable carbon-holder and a truck, the carbons of each holder being interleaved with a set of work-webs, and spacers carried by the rear truck, adjacent each of the sides thereof for disposing the rear carbon-holder in spaced relation to said rear truck, whereby to provide a channel through which the work-webs of the front carrier have passageway.

2. In a continuous billing typewriting machine, in combination, a platen around

- which may be fed separate sets of work-webs, a platen-carriage including a rearward extension, a front carbon-carrier and a rear carbon-carrier, each of said carriers including a tuck and a superposed removable carbon-holder, the carbons of each holder being interleaved with a set of work-webs, and spacing means interposed between the top of said rear truck and the under side 10 of its associated carbon-holder to provide a passageway through which to feed the webs of the front carrier, thereby permitting the rear carbon-holder to be removed from its truck for substitution of a new carbon-holder and work-webs, without disturbing the front carbon-carrier or its work-webs.
3. In a continuous billing typewriting machine, in combination, a platen around which may be fed separate sets of work-webs, a 20 platen-carriage including a rearward extension, a front carbon-carrier, and a rear carbon-carrier, both slideable on said extension, the carbons of each holder being interleaved with a set of work-webs, said rear carbon-carrier including a truck, a pair of spacers secured to the upper surface of said truck adjacent both sides thereof and each having a perforation therein, a carbon-carrying bracket-plate arranged to rest upon said 30 spacers and including pins to engage in said perforations, said pins having slots beneath said spacers, and a blade pivoted to each of said spacers to engage said slots for securing the bracket-plate in spaced relation upon 35 the truck, whereby a passageway is provided between said bracket-plate and its truck through which to feed the work-webs associated with the front carbon-carrier and enabling easy removal of said bracket-plate 40 and its associated work-webs without disturbing the work-webs of said front carbon-carrier.
4. In a continuous billing typewriting machine, in combination, a platen, a platen-carriage, a rearward extension thereof, a plurality of carbon-carriers slideable on said extension, a deflector adjacent the rear of the typewriter for directing the leading portions of work-webs associated with one of said carriers downwardly and beneath said extension when said webs are out of use.
5. In a continuous billing typewriting machine, in combination, a platen, a platen-carriage, a rearward extension thereof, a plurality of carbon-carriers slideable on said extension, means adjacent the rear of the typewriter for deflecting and guiding the leading portions of work-webs downwardly beneath said extension, and a table arranged 55 to receive said leading portions to support the same when out of use.
6. In a continuous billing typewriting machine, in combination, a platen, a platen-carriage, a rearward extension thereof, a front carbon-carrier and a rear carbon-carrier,
- means adjacent the rear of the typewriter whereby the leading portions of work-webs associated with the front carrier may be deflected downwardly and beneath said extension, and a support beneath the latter upon 70 which said webs may rest when out of use.
7. In a continuous billing typewriting machine, in combination, a revolvable platen, a platen-carriage, a rearward extension thereof, a plurality of carbon-carriers slideable on 75 said extension, and a table beneath said extension, said table including a platform and a portion turned upwardly adjacent the rear of the typewriter to provide a deflector for directing the leading portions of work-webs 80 associated with one of said carriers downwardly and onto said platform.
8. In a continuous billing typewriting machine, in combination, a revolvable platen, a platen-carriage, a rearward extension thereof, a table disposed beneath the extension and including legs securing the table to said extension, and a paper-table behind 85 said platen, said first-named table having a portion thereof curved upwardly to said paper-table for deflecting the leading edges of work-webs downwardly and onto the first-named table when out of use.
9. In a continuous billing typewriting machine, in combination, a revolvable platen, 90 a platen-carriage including a rearward extension, a plurality of carbon-carriers slideable on said extension, and a table secured beneath and arranged to travel with said carriage for the reception of the leading portions of work-webs of one of said carriers when out of use.
10. In a continuous billing typewriting machine, in combination, a platen, a platen-carriage, a rearward extension thereof, a plurality of carbon-carriers on the extension, a deflector secured to said extension adjacent the rear of the typewriter, and a table associated with said deflector and disposed beneath said extension.
11. In a continuous billing typewriting machine, in combination, a platen, a platen-carriage including a rearward extension, a plurality of carbon-carriers on the extension, and a table disposed beneath and movable with said carriage for supporting the leading portions of work-webs associated with one of said carriers when not in use.
12. In a continuous billing typewriting machine, in combination, a revolvable platen, a platen-carriage, a rearward extension thereof, a front carbon-carrier and a rear carbon-carrier slideable on the extension, a deflector secured to said extension adjacent the rear of the typewriter for directing the leading portions of work-webs associated with said front carrier downwardly beneath said extension, and a table formed with said deflector upon which said work-webs are received and carried when out of use.

13. In a continuous billing typewriting machine, in combination, a revoluble platen, a platen-carriage including a rearward extension, a rear carbon-carrier, a front carbon-carrier, a clip adjustably secured to the rear portion of said extension, and a pin carried by said rear carrier around which said clip engages to hold said rear carrier against movement while the front carrier is being manipulated.

14. In a continuous billing typewriting

machine, in combination, a revoluble platen, a platen-carriage, a rearward extension of the carriage including a pair of rails, a rear carbon-carrier, a front carbon-carrier, a detent adjustably secured adjacent the rear end of one of said rails, and a pin carried by said rear carrier and arranged to engage said detent to hold said rear carrier immovable during the reciprocation of the front carrier. 15 20

JESSE A. B. SMITH
